US00D688963S

(12) **United States Design Patent**
Hanson et al.

(10) **Patent No.:** **US D688,963 S**
(45) **Date of Patent:** **** Sep. 3, 2013**

(54) **SAMPLING MACHINE**

(71) Applicants: **Royal A. Hanson**, Chatsworth, CA (US);
Steven W. Shaw, Simi Valley, CA (US);
Robson L. Splane, Jr., Valley Center,
CA (US); **Jeff Rosenbohm**, Omaha, NE
(US); **William P. Debley, Jr.**,
Northridge, CA (US)

(72) Inventors: **Royal A. Hanson**, Chatsworth, CA (US);
Steven W. Shaw, Simi Valley, CA (US);
Robson L. Splane, Jr., Valley Center,
CA (US); **Jeff Rosenbohm**, Omaha, NE
(US); **William P. Debley, Jr.**,
Northridge, CA (US)

(**) Term: **14 Years**

(21) Appl. No.: **29/438,716**

(22) Filed: **Dec. 3, 2012**

(51) **LOC (9) Cl.** **10-04**

(52) **U.S. Cl.**

USPC **D10/81**; D24/232

(57) **CLAIM**

The ornamental design for sampling machine, as shown and described.

DESCRIPTION

FIG. 1 is a perspective view of the sampling machine

FIG. 2 is a front view of the sampling machine

FIG. 3 is a first side view of the sampling machine

FIG. 4 is a second side view of the sampling machine

FIG. 5 is a top view of the sampling machine

FIG. 6 is a rear view of the sampling machine; and,

FIG. 7 is a bottom view of the sampling machine.

1 Claim, 7 Drawing Sheets

FIG. 1

FIG. 2

FIG. 3

FIG. 4

FIG. 5

FIG. 6

FIG. 7
